UNITED STATES PATENT OFFICE.

FREDRICK HANSON AND CHARLES FREIHOFER, OF PHILADELPHIA,
PENNSYLVANIA.

DESIGN FOR A BAKING-PAN.

SPECIFICATION forming part of Design No. 33,960, dated January 22, 1901.

Application filed October 13, 1900. Serial No. 33,012. Term of patent 14 years.

To all whom it may concern:

Be it known that we, FREDRICK HANSON and CHARLES FREIHOFER, citizens of the United States, and residents of Philadelphia, Pennsylvania, have invented and produced 5 a certain new and original Design for a Baking-Pan, of which the following is a specification.

Our design for the body of a baking-pan is 10 clearly illustrated in the accompanying drawings, in which—

Figure 1 is a plan view of a baking-pan, illustrating our design. Fig. 2 is a side view.

The essential features of the design are the 15 elongated shape of the pan, the rounded ends, the flat bottom, and the corrugated sides.

A is the baking-pan, having a flat bottom *a*, tapered ends, and sides *b*. The ends are

rounded, as shown. The sides and ends have vertical corrugations *d*. The ribs formed by 20 the corrugations are rounded, as shown, giving the effect clearly illustrated in the accompanying drawings.

We claim—

The design for a baking-pan as herein described and as illustrated in the accompanying 25 drawings.

In testimony whereof we have signed our names to this specification in the presence of two subscribing witnesses.

FREDRICK HANSON.
CHARLES FREIHOFER.
